UNITED STATES PATENT OFFICE.

PAUL E. WHITE, OF LOS ANGELES, CALIFORNIA.

ADVERTISING DEVICE.

SPECIFICATION forming part of Letters Patent No. 656,131, dated August 14, 1900.

Application filed September 25, 1899. Serial No. 731,669. (No model.)

To all whom it may concern:

Be it known that I, PAUL E. WHITE, a citizen of the United States, residing at Los Angeles, in the county of Los Angeles, State 5 of California, have invented a new and useful Improvement in Advertising Devices, of which the following is a specification.

My invention relates to an advertising device to which a blotter is attached; and it 10 consists in the novel arrangement of the several parts hereinafter described, and illustrated in the accompanying drawings, forming part hereof, in which—

Figure 1 is a plan view of my advertising- 15 blotter. Fig. 2 is a side view of the same. Fig. 3 is a central vertical cross-section.

A is a yielding frame or support to which the blotter B is removably affixed by the spring-clips D, affixed to the frame. The 20 lower part of this frame is preferably semi-elliptic in vertical longitudinal section, having at either end thereof an upwardly-curved extension A', to which the handle C is affixed. This handle is composed of two revoluble 25 drums E, journaled in the ends of the handle, around which rollers a band or strip F is placed, and it is wound and unwound by means of the milled thumb-pieces G. On this band various classified advertisements 30 (comprising a directory of the various trades, professions, and callings, where used) are printed. These advertisements are interposed between statistical facts and data of universal interest printed on the band, such 35 as weights and measures, rates of postage, fire-alarm boxes, legal holidays, &c. In rotating these drums the band is wound upon one drum and unwound from the other, exposing to view different advertisements and 40 matter printed thereon.

A flat friction-spring H extends from the journal of one drum to the journal of the other drum and is spring-pressed against these journals by the thumb-screw I to any 45 suitable degree of pressure to prevent any unnecessary rotation of either drum. This will cause the upper or exposed portion of the band F to remain taut and always expose a straight flat surface, on which the advertisements and other matters are printed. Surrounding the drums and comprising part 50 of the handle is the transparent shell J, which

protects the band from injury and dirt and at the same time permits the advertisements and matter printed thereon to be seen. Under the handle and on the inner side of the frame A and in open view to the user of the blotter is a printed calendar of the current year. This calendar may be pasted on the inner side of the frame, or it may be printed 55 thereon.

The advertisements are preferably printed in alphabetic or numerical order, according to the subject-matter, or otherwise, and an index of the subject-matter may for convenience 60 be placed on the frame A in addition to the calendar of the current year.

Having described my invention, what I claim as new, and desire to secure by Letters Patent, is—

1. A blotter adapted to display advertisements comprising a yielding frame having an inner and outer face semi-elliptic in cross-section and having upturned extensions provided with clasps to hold a blotter against the 75 outer face of the frame, a blotting-pad interposed between the clasps and the frame, the inner face of the frame adapted to receive and display matter printed thereon, a handle for said blotter attached at each end to the 80 upturned extensions of the frame and having an outer transparent shell or casing, two drums journaled in said casing and provided with means for their rotation, a strip containing printed matter surrounding said drums, 85 a friction-spring resting on the axes of said drums and provided with means to adjust the pressure exerted by the spring on the axes.

2. The herein-described advertising device comprising a semi-elliptic yielding frame A 90 having upturned extensions A' and having also affixed thereto clips D adapted to hold a blotting-pad interposed between them and the frame, in contact with the frame, a blotting-pad B placed therein, the inner surface 95 of the frame arranged to receive and retain a printed calendar of the current year or other printed matter, a calendar and other printed matter printed thereon, a handle C extending from one end of the frame to the other end and connecting with extensions A', the outer casing or shell J of the handle being composed of transparent material, two drums E revolvably mounted in bearings in said handle and being 100

provided with thumb-pieces G projecting therefrom for rotating the same, a band or strip F containing advertisements and printed matter thereon wound on said drums and adapted 5 to be unwound from one drum and wound upon the other drum, displaying meanwhile the advertising and other matter printed thereon, a spring H resting on the axes of said drums and adapted to bear against said axes, 10 a spring-adjusting thumb-screw I arranged to bear against said spring when screwed

down against the spring and prevent the drums from any unnecessary rotation.

In witness that I claim the foregoing I have hereunto subscribed my name this 16th 15 day of September, 1899, at San Bernardino, California.

PAUL E. WHITE.
